SELF-INDUCTANCE DEVICE

Ernst Reiser, Berlin, Germany, assignor to C. Lorenz Aktiengesellschaft, Berlin-Tempelhof, Germany, a company

Application March 31, 1938, Serial No. 199,145
In Germany April 3, 1937

7 Claims. (Cl. 171—119)

The present invention relates to self-inductance devices and particularly to arrangements having cores of high-frequency iron.

The use of a sheath-formed body of high-frequency iron-dust encompassing the winding is a known expedient in connection with self-inductance coils. It is also known to provide the high-frequency iron-dust core with an air gap of variable size for balancing the self-induction of different coils, so as to obtain coincidence of operation. The known structures of this type generally employ the high-frequency iron-dust core as the support for the adjusting means which may be a threaded rod of high-frequency iron arranged to be screwed more or less into the coil, but the thread which has been cut in the compressed iron dust will likely be damaged by vibrations affecting the devices with the result that the value of the self-induction is subjected to changes. Moreover, these known arrangements either present very low capability of adjustment or involve considerable capacitive de-tuning on regulation.

These disadvantages are obviated according to the invention which employs a high-frequency iron-dust magnetic structure made in several separate parts, said parts being arranged in a container of insulating material, preferably of tubular shape. This container is closed by a cover which serves not only for maintaining the various parts in position but also as support for a balancing disc. Induction changes up to 20 per cent may be obtained by this arrangement by suitably chosen cross sectional areas of the iron and an adequate stroke of the balancing disc.

The container of insulation may according to a further feature of the invention also serve as support for a second coil through which a small part only of the lines of force of the coil with iron core flows. This arrangement constitutes a high frequency transformer which permits a low degree of coupling. The turns of this coil may be located in the lower part of the insulating body external to the high-frequency magnetic sheath surrounding the main coil. This arrangement is particularly advantageous since the second coil comprises for a given small degree of coupling a relative large number of turns which provide suitable balancing properties.

The invention will be fully understood from the following description taken in conjunction with the accompanying drawing, in which:

Fig. 1 represents a longitudinal cross section through a self-inductance device according to the invention, Fig. 2 shows a top view of the

arrangement of Fig. 1, while Fig. 3 is a longitudinal cross section through a coupling transformer in accordance with the invention.

Referring first to Figs. 1 and 2, reference numeral 1 designates an insulating body of substantially tubular shape which serves as a support for a coil 2. The desired number of turns are arranged on an insulating member 15 which may be of Bakelite or the like. The coil is placed on a core 14 of high-frequency iron fitted in a high-frequency iron-dust base plate 3. A tubular sheath 4 of similar material surrounding the coil is closed by a movable disc 5 also of similar material adapted to effect balance. The tubular sheath 4 and the base plate 3 are fixed in position by a cover disc 6 threaded into the insulating body 1. The base plate 3 is provided with a slot which is adapted to receive a nose 7 provided integral with the body 1 at its lower end, so as to prevent angular displacement therebetween. The cover disc 6 of insulation carries a set screw 8 likewise of insulating material. The balancing disc 5 is fixed to the lower end of said screw. The inductance value of the coil is balanced by turning the screw 8.

The above disclosed arrangement provides a reliable supporting means for all separate members of high-frequency iron. Two longitudinal projections 9 are formed integral with the body 1 of insulation and serve for fixing the self-inductance coil. A further circumferential extension 10 likewise integral with the body 1 is adapted to receive the soldering tabs 11 clamped thereto.

Fig. 3 illustrates a transformer arrangement similar to the above described self-inductance coil arrangement, the individual elements of which carry the same designations as those shown in Figs. 1 and 2. However, the base portion of the insulating body 1 has in this arrangement been replaced by a flat frame or body 12 carrying a second winding 13. In order to avoid capacitive de-tuning of the coupling coil 13, which may be set up when the coil is placed on metal for example, a further iron disc 3' is located below this coil. This arrangement involves the advantage that the same elements may be utilized as in connection with the simple self-inductance device according to the Figs. 1 and 2 and, moreover, the frequently desired requirement of a low degree of coupling may be secured thereby.

The insulating container and its projections are preferably produced in one manufacturing operation.

What is claimed is:

55

1. A self-inductance device as defined in claim 6, in which said casing element carries a circumferential extension formed integral therewith and a plurality of soldering tabs clamped to said extension.
2. A coupling transformer comprising a magnetic structure of high-frequency magnetic dust including a base plate, a centre core fixed perpendicularly to said base plate and a tubular sheath extending perpendicular to said base plate around said core, a container of insulation surrounding said magnetic structure, a cover screwed into the upper end of said container, said cover and container being shaped and positioned to firmly clamp the magnetic structure between them, a balancing disc supported solely from said cover, a second winding arranged on a base plate removably associated with said container and a magnetic disc adjacent to said second winding on the opposite side thereof from said magnetic structure.
3. A high-frequency adjustable inductance device of the type having two flux-carrying parts movable with respect to each other, which comprises a winding, a plate-like base element of compressed magnetic dust disposed transversely at one end of said winding, a separate tubular sheath of compressed magnetic dust substantially coaxially surrounding said winding and extending to said base element at one end and beyond the end of said winding at its other end, a casing element of insulating material around said sheath shaped to firmly engage both said base element and said sheath to hold them in fixed relation to each other and to said casing element, a core of compressed magnetic dust supported inside said winding, and a disc-like adjusting member disposed at the end of the winding remote from said base element and supported solely from said casing element adjustably for movement within said sheath.
4. An inductance device according to claim 3, wherein said core is fixed to said base member independent of said casing element and said disc-like adjusting member.
5. An inductance device according to claim 3, wherein said casing element and said base element are formed with projections on one of said elements and corresponding recesses on the other of said elements shaped to fix said two elements against relative rotary movement.
6. A high frequency adjustable inductance device which comprises a winding, a plate-like base element of compressed magnetic dust disposed transversely at one end of said winding and extending beyond the circumference of said winding, a separate tubular sheath of compressed magnetic dust substantially coaxially surrounding said winding and extending to said base element at one end and beyond the end of said winding at its other end, a two-part casing element of insulating material around said sheath including a body member and a cover member threaded thereto, said combined element being shaped to clampingly engage both said base element and said sheath to hold them in fixed relation to each other and to said casing element, a core of compressed magnetic dust supported inside said winding, and a disc-like adjusting member disposed at the end of the core remote from said base element and supported solely from said casing element adjustably for movement within said sheath.
7. An inductance device according to claim 6, wherein said core is fixed to said base element and which further comprises a screw of insulating material threaded through said casing element and fixed to said disc-like member for adjustably supporting said member for axial movement toward or away from said winding and core.
